UNITED STATES PATENT OFFICE.

DESIRE H. VAN HOVE, OF JACKSON, MICHIGAN, ASSIGNOR TO THE REYNOLDS SPRING COMPANY, OF JACKSON, MICHIGAN, A CORPORATION OF DELAWARE.

SPRING STRUCTURE.

1,387,744.

Specification of Letters Patent. Patented Aug. 16, 1921.

Application filed February 25, 1921. Serial No. 447,754.

To all whom it may concern:

Be it known that I, DESIRE H. VAN HOVE, a citizen of the United States, residing at Jackson, in the county of Jackson and State 5 of Michigan, have invented new and useful Improvements in Spring Structures, of which the following is a specification.

This invention relates to spring structures.

One object of the invention is to provide 10 a spring structure for automobile or other seats, embodying among other characteristics, upper and lower frames connected together by relatively stiff border springs within which is disposed a group of springs 15 of shorter length surrounded by an intermediate frame, constituting a deck of auxiliary springs within the border springs and upon which deck may be loosely mounted a cushion which may fit within the confines of 20 the upper portions of the border springs and which may consist of pocketed springs.

Another object of the invention resides in 25 the provision of a spring structure including a base frame, relatively stiff border springs connected to the base frame, a deck of relatively short springs on the base frame within the border springs, and arranged to provide a recess in the top of the structure for the 30 reception of a cushion adapted to be mounted directly upon said deck of springs, the cushion being composed preferably of cylindrically shaped springs of very light gage wire with each spring arranged within a pocket of fabric or separated by a fabric or 35 other suitable material to prevent the springs from rubbing against one another and causing a noise.

A still further object is to provide a spring 40 structure having a comparatively stiff edge and an exceedingly soft and pliable center to provide for the ease and comfort of the rider.

With these and other objects in view the 45 invention consists in the novel construction, combination and arrangement of parts hereinafter fully described, illustrated in the accompanying drawings and pointed out in the claims hereto appended, it being understood that various changes in the form, proportion, and minor details of construction, within 50 the scope of the claims, may be resorted to without departing from the spirit or sacrificing any of the advantages of the invention:

In the drawings, in which like characters 55 of reference designate corresponding parts in the several figures,

Figure 1 is a top plan view of the invention.

Fig. 2 is a transverse sectional view. 60

Referring now more particularly to the accompanying drawings, the reference character 5 indicates an upper border frame of wire or any other suitable material and 6 indicates a base frame of any suitable construction. 65

Border springs 7 are mounted between the upper and lower frames and supported at their bottoms upon any suitable forms of supporting members 8 and being clipped at 70 their upper ends as at 9 to the upper frame.

A group of relatively short springs 10 are mounted upon said supporting members 8 and may be of double cone or other type and are of a height substantially one-half the 75 height of the border springs 7. A frame 11 may be connected to the upper convolutions of the springs 10 forming a border for the upper ends of the said springs. This frame may be connected by links 12 to the border 80 springs so as to prevent the lateral shifting of the border frame 11 and the group of springs 10. If desired, a wire cloth or other netting 13 may be connected to the border frame 11 across the other ends of the group 85 of springs 10. This group of springs 10 with their frame 11, with or without the netting 13, form what constitutes a deck 90 within the structure and within the confines of the upper portions of the border 95 springs.

A cushion is adapted to be supported within the structure upon said group or deck of springs 10. This cushion preferably consists of pocketed springs. In any event the 95 cushion is composed preferably of relatively light gage wire springs confined within an enveloping member such as fabric. In one embodiment of the invention, the cushion is composed of rows of very light cylindrical 100 shaped springs 14, arranged close together, with parallel strips of cotton, canvas or any other suitable fabric 15 arranged between adjacent rows of springs to prevent direct contact of the convolutions of one row of springs 105 with the convolutions of the row of adjacent springs and thereby preventing noise. A marginal strip of cotton canvas or other fab-

ric material 15' incloses the outer springs 14. The upper and lower edges of the marginal strip 15' and the upper and lower ends of the vertical strips of fabric 15 are connected 5 to upper and lower sheets of burlap or other suitable material 16 and 17, respectively.

When the cushion is thus formed it is let down into the spring structure and rests directly upon the group or deck of springs 10, overhanging the border frame 11 with the edges of the cushion lying close to the border springs. This cushion may be connected to the border springs or other upper frame or in any other manner fastened. 15 against accidental removal from off the deck of springs 10 as for instance, if the structure should be turned upside down or set on one edge. In actual use of the structure, there is no necessity of fastening the same to the spring structure, because in the customary methods of upholstering, the upholstering cover, together with the upholstering material, would maintain the cushion in proper place.

25 From the foregoing it will be seen that there is provided an exceedingly resilient and soft spring cushion for automobiles or other purposes. The border wires are relatively stiff and the center of the structure is exceedingly soft and pliable, particularly in view of the relatively light gage wire of which the cushion springs are composed. The structure may be said to consist of a spring structure embodying a frame, border 30 springs, a lower deck of springs, and an upper deck of springs, the upper deck being readily detachable with relation to the lower deck of springs, and the upper deck being composed of springs of considerably 35 lighter gage wire than the springs of the lower deck, thereby providing for softness, pliability and providing for ease and comfort for the rider.

What is claimed is:

45 1. In a spring structure, an upper frame, a lower frame, border springs arranged within the upper and lower frames, a group of lower springs arranged between the frames and within said border springs, a group of upper springs arranged within the frame and within the border springs and mounted upon 50 said lower group of springs, the upper springs of said group being of lighter gage wire than the springs of the lower group, 55 and strips of fabric arranged between the springs of said upper group of springs to prevent noise.

60 2. In a spring structure, an upper frame, a lower frame, border springs arranged between the frames, a group of lower springs arranged within the border springs, and a fabric covered set of relatively light gage wire springs arranged close together and supported upon said lower group of springs.

65 3. In a spring structure, an upper frame,

a lower frame, border springs arranged between the frames, groups of upper and lower springs arranged between the frames and within the border springs, the springs of the upper group being of lighter gage 70 wire than the springs of the lower group, confined in pockets, a frame arranged between the aforesaid frames and connected to the upper ends of the lower group of springs, a sound deadening material stretched across 75 the second mentioned frame, and connections between said second mentioned frame and certain of the border springs.

4. In a spring structure, a frame, border springs on the frame, a group of springs arranged within the border springs and of less height than the border springs, and a cushion arranged within the border springs and mounted upon said group of springs and composed of springs of relatively light 80 wire, all of the springs of said cushion being pocketed in fabric. 85

5. In a spring structure, a base frame, border springs connected to the base frame, a group of springs of less height than the 90 border springs forming a deck within the border springs, and a cushion composed of springs and fabric adapted to rest on said deck and within the border springs.

6. In a spring structure, a frame, border 95 springs, mounted upon the frame, a group of lower springs arranged on the frames and within the border springs, and a fabric covered set of relatively light gage wire springs arranged close together and supported upon 100 said lower group of springs.

7. In a spring structure, a frame, border springs arranged on the frame, a group of lower springs arranged on the frame and within said border springs, a group of upper 105 springs arranged between the frame and within the border springs and supported on said lower group of springs, the upper group of said springs being of lighter gage wire than the springs of the lower group and 110 means between said upper and lower groups of springs to prevent noise.

8. In a spring structure, a frame, border springs supported on the frame, a group of springs of less height than the border 115 springs arranged within the border springs and forming a deck, a frame for said group of springs, connected at the upper ends of the latter, and an inclosed group of springs arranged within the border springs 120 and supported upon the deck formed by the aforesaid group of springs.

9. In a spring structure, a base frame, border springs of relatively stiff wire mounted on the base frame, a group of relatively 125 stiff springs mounted within the border springs and of a height substantially half the height of the border springs, connections between said groups of springs and the border springs, a soft pliable cushion adapt- 130

ed to rest upon said group of springs and lie within the border springs, said cushion being composed of covered springs.

10. In a spring structure, a frame, border springs within the frame, a group of springs substantially one-half the height of the border springs and arranged within the lat-

ter and an inclosed group of springs removably arranged within the border springs and supported upon the deck forming the 10 aforesaid group of springs.

In testimony whereof I have hereunto set my hand.

DESIRE H. VAN HOVE.
